(57) CLAIM

The ornamental design for a portion of a shoe upper, as shown and described.

DESCRIPTION

FIG. 1 is a perspective view of a portion of a shoe upper showing my new design;

FIG. 2 is a side elevational view thereof;

FIG. 3 is a top plan view thereof;

FIG. 4 is a front elevational view thereof; and,

FIG. 5 is a rear elevational view thereof.

The uneven broken line immediately adjacent to the shaded area represents a boundary of the claimed design. The uneven broken line showing of the eyelet element and the remainder of the shoe is for illustrative purposes only and form no part of the claimed design.
